UNITED STATES PATENT OFFICE

JOHN E. COFFIN, OF PORTLAND, MAINE.

IMPROVEMENT IN MATCH CARDS OR SPLINTS.

Specification forming part of Letters Patent No. 148,109, dated March 3, 1874; application filed January 3, 1872.

To all whom it may concern:

Be it known that I, JOHN E. COFFIN, of Portland, in the county of Cumberland and State of Maine, have invented a new and Improved Match Card or Splint, of which the following is a specification:

This invention consists of a match card or splint composed of a single row of matches, in which each match is divided from the other by a single incision only, extending entirely through the thickness of the blank for the greater portion of the length of the match, leaving the bottom part of the blank or card uncut, as hereinafter shown and described.

In the accompanying drawing, Figure 1 is a perspective view, and Fig. 2 a section, of a match-card made in accordance with my invention.

A is the wooden card-blank; b b, &c., the longitudinal cuts or incisions, and c c, &c., the matches produced by such cuts. The incisions b b, &c., are not extended the entire length of the card A, but terminate at a point more or less remote from the base of the card, in order that, by leaving the bottom portion of the latter intact, the matches shall be caused to adhere together by the natural grain of the wood with all desirable tenacity.

The distinctive feature of my invention lies in the card composed of a single row of matches formed by incisions b, as described, in contradistinction to saw or other cuts, which will remove from the card and from between the matches a portion of the material. In a match-card thus made, the matches hold together without requiring the application of glue or other adhesive material to the bottom of the card, or

without requiring the uncut end of the card to be hammered or pounded in order to mat together the fibers, and the blank requires no previous treatment by boiling or steaming in order to fit it to be acted on by the knife. There is also a saving in material of from ten to thirty-three per cent. over the ordinary sawed match-card, as in my card the knife cuts or incisions b cause absolutely no loss of material.

I have not in this specification described any special machinery for making the card, as I design to make that the subject-matter of separate Letters Patent.

I do not claim a sawed match-card, nor a match-card in which the matches are partly separated from one another by cuts extending the length of, but only partly through the thickness of, the matches, as described in Hotchkiss's patent of June 13, 1865, nor a match-block composed of several rows of matches, whether separated from each other by sawing or splitting; but

What I do claim, and desire to secure by Letters Patent, is—

A match card or splint composed of a single row of matches, in which each match is divided from the other by a single incision only extending through the thickness of the blank for the greater portion of the length of the match, leaving the lower portion of the card uncut, as herein shown and described.

JOHN E. COFFIN.
